[57] CLAIM

The ornamental design for the humidor, as shown and described.

DESCRIPTION

FIG. 1 is a front elevational view of a humidor with the lid open showing my new design;

FIG. 2 is a side elevational view thereof with the other side being a mirror image thereof;

FIG. 3 is a top elevational view thereof;

FIG. 4 is a bottom elevational view thereof;

FIG. 5 is a perspective view of a humidor with the lid open;

FIG. 6 is a perspective view of a humidor with the lid closed showing my new design; and,

FIG. 7 is a cross section of a front elevational view of a humidor with the lid closed showing my new design.

1 Claim, 4 Drawing Sheets

FIG. 2.

FIG. 1.

FIG. 3.
